(57) **CLAIM**

We claim the ornamental design for an electrical component
with alternating current output, as shown and described.

DESCRIPTION

FIG. 1 is a front side view of the electrical component with
alternating current output;

FIG. 2 is a left side view thereof;

FIG. 3 is a right side view thereof;

FIG. 4 is a top side view thereof;

FIG. 5 is a bottom side view thereof;

FIG. 6 is a rear side view thereof;

FIG. 7 is a front, left, top isometric view thereof; and,

FIG. 8 is a front, right, bottom isometric view thereof.

The broken lines in the drawings are for illustrative purposes
only and form no part of the claimed design.

The broken line(s) which define the bounds of the claimed
design form no part thereof.
